UNITED STATES PATENT OFFICE.

ROBERT F. COOKE, OF BROOKLYN, NEW YORK, ASSIGNOR TO HORACE HOLDEN, OF EAST ORANGE, NEW JERSEY.

LIGHTING DEVICE.

SPECIFICATION forming part of Letters Patent No. 326,852, dated September 22, 1885.

Application filed December 29, 1884. (No model.)

To all whom it may concern:

Be it known that I, ROBERT F. COOKE, of Brooklyn, in the State of New York, have invented a new and useful Improvement in Match-Cases, of which the following is a specification.

Figure I represents a longitudinal section of my improved match case on an enlarged scale. Fig. II is an outside view of the case. The other figures are details referred to in the following specification.

Similar letters represent similar parts in all the figures.

Into a suitable casing, A, a tube, B, is inserted, made to slide easily in the same, and closed at its lower end by a cap-piece, C, screwed upon the same. In the case a small projection, a, is provided, and a long slot, b, is made in the tube B, Fig. IV, in which the projection a works, to prevent the tube B from turning and to regulate the amount of its motion. The upper end of this tube B is made funnel-shaped, as at c, and has a smaller tube, B', corresponding to the size of the match attached. To the outside of this tube B' a spring-rod, D, with a small sharp point, d, at its upper end, is attached. (See Fig. III.)

To the upper end of the case A a small tube, A', is attached, to which a tube, F, is fastened. This tube F, Figs. V and VI, which is of sufficient size to allow the tube B' to pass freely through it, is provided with a slot, n, extending the whole of its length, to allow the free passage of the spring-rod D, and has two spring-rods, E E, opposite each other attached to its outside. The upper ends of these spring-rods are made flat and project through suitable openings into the tube F, nearly meeting at its center. To the upper end of this tube F sharp spring-points G, Figs. I and VII, surrounding the tube F, except at the place where an opening is left for the spring-rod D to pass, are securely attached, the points all pointing toward the center. A removable cap, H, is arranged at the upper end of the case A, enclosing these spring-points.

The tube B is filled with suitable matches, (fully described in another application for a patent, filed December 29, 1884, Serial No.

151,484,) N, attached to each other by a string, so that the matches will be gradually pulled out of the case B. The manner in which these matches are arranged, tied together, and packed afterward into a cartridge-case is shown in Figs. VIII and IX, where in Fig. VIII they are shown side by side, and in Fig. IX a top view as hinged together in the case. When one of the matches has been pushed past the points G and ignited, the next match N is supported upon the flat ends of the spring-rods E E. The tube B being then pulled downward to its fullest extent will bring the pointed end of the spring-rod D below the bottom of the match N, supported upon the ends of the spring-rods E E, and which said rods will prevent said match being pulled downward by the downward movement of the tube B, while by that operation another one of the matches contained in said tube B will be drawn upward. The pointed end of the spring-rod D will fasten itself against the bottom of the match N by the upward motion of the tube B and B', to which said rod D is attached, and thus push the match N upward between the sharp points G, thereby igniting the same.

As before stated, the matches are attached to each other by a string, in consequence of which, while the match N is pushed upward through the sharp points G, the next match will force the spring-rods E E apart to allow it to pass, and comes then above the flat ends of said spring-rods to be supported by the same ready for the next operation.

What I claim as my invention, and desire to secure by Letters Patent, is—

In combination with a suitable case, A, the sliding tubes B B', with spring-rod D, the tube F, with spring-rods E E, and the sharp pointed projections G, the whole being arranged to operate in combination with matches attached to each other by a string, in the manner and for the purpose substantially as described.

ROBERT F. COOKE.
